UNITED STATES PATENT OFFICE.

GREGORY JENNINGS, OF WEST CAIRO, OHIO.

TILE-KILN.

SPECIFICATION forming part of Letters Patent No. 311,660, dated February 3, 1885.

Application filed October 20, 1884. (Model.)

To all whom it may concern:

Be it known that I, GREGORY JENNINGS, of West Cairo, in the county of Allen and State of Ohio, have invented a new and useful Improvement in Tile-Kilns, of which the following is a full, clear, and exact description.

My invention consists in certain novel features of construction in kilns for burning tiles, having the object to permit regulation of the heat, and consequently the proper burning of the tiles, as hereinafter described and claimed.

Reference is to be had to the accompanying drawings, forming a part of this specification, in which similar letters of reference indicate corresponding parts in all the figures.

Figure 1 is a sectional plan view of a kiln of the improved construction. Fig. 2 is a vertical section of the same, and Fig. 3 is a detail section.

The kiln is of a circular form, with walls A built upon a suitable foundation, and around the walls at the bottom are built the series of fire-boxes and air-boxes B C. The boxes B connect with the internal draft-pipes, D, and the air boxes or chamber C connect with two arches, E, that cross each other at the bottom of the kiln. The arches E are connected by the curved arches F, which are set apart, so as to form circular air-chambers that insure uniform draft throughout. The air-boxes C are provided with flues G, rising at the outside of the kiln, and, except when cleaning out, these boxes C are closed at their outer ends. At H is the entrance to the kiln, which is closed by a double brick-wall filled in with ashes during the burning, and a tile is inserted through a hole in the wall as a peep-hole. Near the top of wall A is a peep-hole,

I, for use in watching the operation, so that 40 the proper time for changing the draft can be ascertained. At boxes C are dampers K, for cutting off the flues G. By opening and closing these dampers the draft is changed, the hot air going out or cold air rushing in at the 45 peep-hole I. By this construction and arrangement of the flues and arches a downward draft can be used and changed as necessary in order to burn the tiles hard at the bottom and not too hard in the top part of the kiln. 50 The cross-arches and air-spaces insure an even degree of heat at the center and sides of the kiln. The floor for receiving the tiles is formed by setting bricks on the arches E F. In the crown of the kiln there are holes for 55 exit of the workmen, which are to be closed, and only opened to cool off the kiln. These holes may, if it is desired to change to an updraft kiln, be left open and the flues be arranged accordingly.

Having thus described my invention, I claim as new and desire to secure by Letters Patent—

In a tile-kiln, the body A, in combination with the fire-boxes B, arranged externally of said body and having the flues D disposed internally of said body, the external valved air-chambers having external air-flues, G, and flues E, arranged within said body and crossing each other, and the circular air-flues F, connecting said air-flues E from center to circumference of the body and opening into said body above, substantially as and for the purpose set forth.

GREGORY JENNINGS.
